BOBBIN CASE FOR SEWING MACHINES

Daniel H. Chason, Elizabeth, N. J., assignor to
The Singer Manufacturing Company, Elizabeth, N. J., a corporation of New Jersey

Application July 9, 1941, Serial No. 401,580

1 Claim. (Cl. 112—231)

This invention relates to lock-stitch sewing machines and more particularly to bobbin-cases therefor and has for its objective the provision of improved means for preventing the thread from being inadvertently pulled from under the bobbin-thread tension spring when the bobbin-thread is being pulled beneath the spring.

The several features of the present invention will be clearly understood from the following description and accompanying drawing in which:

Fig. 1 is a top plan view of a bobbin-case having my improved tension spring secured thereto.

Fig. 2 is a side elevation of the bobbin-case shown in Fig. 1.

Fig. 3 is a perspective view of my improved tension spring.

In the embodiment of the invention selected for illustration the bobbin-case comprises a cup-shaped body having a cylindrical side wall 1 and a circular end face 2 formed with a groove 3. Located in the groove 3 is a latch 4 which is adapted to hold the bobbin-carrier in the thread basket of a rotary hook of the type illustrated in the patent to Kessler, No. 2,085,699, dated June 29, 1937.

A flat bobbin-thread tension spring, indicated generally as 5 is formed with a centrally arranged bend thereby providing two arms 6 and 7. The arm 6 is secured to the cylindrical wall of the bobbin-case by a screw 8 and an adjusting screw 9 is provided for the purpose of increasing or decreasing the tension on the bobbin-thread T. The free end of the arm 7 of the tension spring is formed with a finger 10 which extends into a circular hole 11 in the cylindrical bobbin-case 1. The edge of the arm 7 of the tension spring is formed with a tang 12 which together with the finger 10 confines the bobbin-thread in the slot 13 therebetween. The tang 12 is located in an open faced slot 19 formed in one end of the latch slot 3.

When the sewing machine operator wishes to replenish the lower thread, a filled bobbin 14 is inserted in the case and the operator draws the issuing end-portion of the thread sidewise into 45 the slot 15 located in the cylindrical side wall of the case and pulls until the thread enters the aperture 16 formed in the side wall 2 and located beneath the arm 7 of the tension spring. A

further pull upon the thread and, at the same time, a movement of the thread to the right, as viewed in Fig. 2, causes the thread to slip sidewise under the finger 10 and into the thread-confining slot 13.

The thread in the position shown in Fig. 2 is the correct position for the bobbin-thread T. However, in prior constructions, because of the haste and carelessness of the operator in threading the bobbin-case, the thread is sometimes pulled so quickly and with so much force that it slips under the exposed and heretofore straight thread-confining tang 12 and therefore from under the effective end of the tension spring. To overcome this unthreading difficulty I have formed the tang with a recess 17 which produces a hook-like end providing a shoulder 18 on the tang. This shoulder prevents the thread from being pulled under the tang 12 and is helped by the location of the tang in the slot 19 which is below the circular face of the thread-case and the pull of the thread and the simultaneous motion to the right causes the thread to lodge in the recess 17 and lie over the shoulder 18 of the tang 12.

While the above described tension spring has been shown and described as applied to a bobbin-case for use in a rotary hook it will be understood that the invention herein set forth is applicable to shuttle cases and all forms of hooks wherein the needle-thread loop is passed around a case carrying a thread-mass.

Having thus set forth the nature of the invention, what I claim herein is:

35 A sewing machine bobbin-case having a cup-shaped body comprising a cylindrical outer wall and a circular end face, said cylindrical wall being formed with an aperture, a thread-tension leaf-spring having a shank end secured to the bobbin-case, said spring having at its free end a finger the end of which is located in the aperture in the cylindrical wall of the case, a tang on said spring and laterally spaced from said finger, said spring having a thread delivery slot between said tang and finger, and the tang being formed with a thread-catching shoulder on the edge thereof adjacent said thread-delivery slot.

DANIEL H. CHASON.
